1 Martin Becker and Thomas Becker

Letters Dated, genuine March 24th 1828.

The advocate agreed to in these - others. To land and making partly
the same containing a description in the words of the said, Martin
Becker and Thomas Becker themselves, their improvement in the said
of curing tobacco.

Improvement in the art of producing tobacco to become you speak
as follows. Some and among the same, by striking, breaking and then
scraping off a small quantity as may be more necessary in the judgment
of the manager to make it sufficiently yellow to become of the tobacco
curing, taking care in all cases not to injure the tobacco to enhance
too much, preference, it is best to let it stand in the field until it is
fully ripe, and when it is cut, take it when about half broken,
and cut it together with the stalks breaking upwards and the leaves
on the ground, to a gentle dry leaves of tobacco spread on the ground
taking care not to cover the tobacco so that it is in such quantities as
to make it to heat, this is called striking, is breaking, and is the
best mode for tobacco that is a part of your culture as follows, when
when cut, it should be covered up in this situation if there be hot
sun, with green bushes or something that will cover the same
sun, sun, and remove, covering from the early eight hours, if the weather
permits, then take it up, laying it on sticks and cover it in covering, a
so that it remains on the ends of the sticks will be all ground, that
scraped off the ground should be covered with nice dry leaves, but you
there be a natural coat of grass sufficient to keep the tobacco from the
dirt, the exposed part of the tobacco should be covered as before, in
this situation it should remain if the weather permits until it
is sufficiently yellow to be cured as the desired color, the sun
ever occasionally examined, says very low or too hot he must see that
it does not get hot, and able to see when it is sufficiently yellow,
then make it in a common high scaffold sufficiently open

X5023

for the air and sun to take off the natural dampness and exhalation while the tobacco was near the ground, it may then be cured by continuation of the sun as by fire, taking care not to let the tobacco be exposed to rain at any time after it is cut, as to do so will communicate earing. If it should be necessary to expose it to weather to carry the tobacco into the house before it is sufficiently yellow, it may be covered in the house until it is in order for curing, as until the weather will permit the fire ought to be used.

Tobacco which has a yellowish appearance in the field when cut, may be put on the fire to offend so soon as it is sufficiently dried to go into the stack, without either smoking or burning.

If the weather is unpropitious for preparing the tobacco for curing, or if the manager prefers having it in the house, there may be prepared in a temporary way so as to keep the heat of the tobacco from exposure to the wind till it becomes yellow.

The improvement in the art of curing is drying tobacco of gray colour by means of tiles as a channel dry in the fire of the house, or by raising floors of stone, brick or stone blocks from the ground to make the floor, which tiles are arranged an covered with sheet iron or the metal.

The preferred mode is to dig three of these channels for a house twenty feet square, six inches into the ground, and having two inches wide, then side joins one foot above ground, the channels to be covered with sheet iron or other metal ten feet wide. The metal to commence about two feet from the wall, the two outside channels are to be about two inches off from the side walls and to the middle two, immediately back of the opposite end of the house from where they commence, from the outside ends of the two outside channels there shall run a channel of the same size and description unbroken in the same way two and a half feet from the wall, &c.

X5023

to be communicated with the shanties running through the centre of the Roode, from which communication there should be a line about eight inches square running through at the bottom of the wall to every one the shanties. This, the wall is to be four inches thick throughout the wall to be made from, brick and concrete with a thickness of four inches.

The first is to be the shanties where the need is to be put in, to extend about one foot outside the wall and be covered with a brick and then the other ends to fit it into the wall line and from the wall. But the number, size and distances of these shanties or shanties as to the plan, as the shanties may be arranged as the convenience of the manager may require, as the size of the houses require.
